[57] CLAIM

The ornamental design for a combined drinking straw and whistle, as shown and described.

DESCRIPTION

FIG. 1 is a front or rear elevational view of a combined drinking straw and whistle showing my new design, it being understood that the corrugated portion thereon follows the pathway of the dotdash lines;

FIGS. 2-7 are transverse cross-sectional views on an enlarged scale taken respectively on lines 2—2, 3—3, 4—4, 5—5, 6—6, and 7—7 of FIG. 1;

FIG. 8 is an enlarged fragmentary elevational view of the upper portion of FIG. 1; and

FIG. 9 is a side elevational view of FIG. 8 taken from the right or left thereof.
